ATTORNEYS

UNITED STATES PATENT OFFICE.

WALTER C. HADLEY, OF NEW YORK, N. Y., ASSIGNOR TO CENTRAL TALKING MACHINE SHOP, INC., OF NEW YORK, N. Y., A CORPORATION OF NEW YORK.

TOY.

Application filed August 20, 1920. Serial No. 404,964.

To all whom it may concern:

Be it known that I, WALTER C. HADLEY, a citizen of the United States of America, and a resident of New York city, borough 5 of Manhattan, county and State of New York, have invented a new and useful Improvement in Toys.

The present invention relates to toys, and it has for its object the production of a 10 toy designed to be supported on and actuated by the keys of an automatic or player piano. As is well known to those familiar with the art, the keys of an automatic or player piano are actuated from their rear 15 end by the instrumentalities operating the hammers, which causes the forward end of the keys to move up and down as a piece of music is played, and one of the objects of the present invention is to utilize this up and 20 down movement of the forward end of the keys to operate the movable parts of a toy resting on the forward end of the keys.

The invention therefore consists of a toy 25 having a movable part actuated by a piano key.

The invention is shown in the accompanying drawing in which Fig. 1 shows one form thereof in front elevation.

Fig. 2 shows a vertical sectional view 30 taken on the line 2—2 in Fig. 1, looking towards the left.

Fig. 3 shows a vertical sectional view taken on the line 3—3 in Fig. 1.

Fig. 4 shows a vertical sectional view of a 35 modified form of the device as shown in Fig. 1.

Fig. 5 shows a front elevation of a portion of the device embodying the modified construction shown in Fig. 4.

Fig. 6 shows a plan view of a portion of 40 the blank employed in manufacturing the modified form of device shown in Figs. 4 and 5.

Fig. 7 shows a front elevation of another 45 form of the device with a portion broken away at one end to show the construction thereunder.

Fig. 8 shows a sectional view taken on the line 8—8 in Fig. 7.

Fig. 9 shows a vertical sectional view 50 taken on the line 9—9 of Fig. 7.

Fig. 10 shows a vertical sectional view taken on the line 10—10 of Fig. 7.

Fig. 11 shows a horizontal sectional view 55 taken on the line 11—11 of Fig. 7.

Fig. 12 shows in front elevation and partial sectional view, another modified form of the device.

Fig. 13 shows a vertical sectional view taken on the line 13—13 of Fig. 12. 60

Fig. 14 shows a horizontal sectional view taken on the line 14—14 of Fig. 12.

Fig. 15 shows a vertical sectional view taken on the line 15—15 of Fig. 12.

Fig. 16 is an underside view of a portion 65 of the device shown in Fig. 12.

Similar reference characters will be employed throughout the specifications and drawings to designate corresponding parts.

The device as shown in Figs. 1, 2 and 3 70 comprises a body portion 1 which, as shown in Figs. 2 and 3, is of triangular shape in vertical cross-section and is formed of any suitable material, such as cardboard. The base 2 of the triangle is relatively narrow 75 and preferably of a width corresponding to the projection of the forward ends of the white keys 3 beyond the black keys 4. The device may be of indefinite length to cover a plurality of adjacent keys, and preferably 80 will be provided with a filler block 5 upon its interior, made of wood or other suitable material, whereby to add weight and to strengthen the construction.

Upon one face of the body portion 1, as 85 shown in Fig. 1, there will be depicted a line of heads 6, extending from the upper jaw 7 upward, the jaw or mouth opening, being located at the base 8 of the front face of the body portion 1. As shown in Fig. 1, these 90 grotesque heads or portions of heads are substantially the width of a white key, and are arranged in a row to represent a group of minstrels or singers. The lower jaw 9 of each head is formed upon the front face 95 of a strip 10. This strip is doubled upon itself as shown at 11 and extends backward and is doubled upon itself as shown at 12, thence extends forward as shown at 13 and is doubled upon itself as shown at 14 100 and has a portion 15 which extends beneath and is secured to the under surface of the base 2 of the body portion (see Figs. 2 and 3). A strip 16 attached to the upper surface of the lower jaw strip, has its free end 105 projecting as shown in Fig. 2 and will be preferably of a red color to indicate the tongue of the figure. The strip 10 will be suitably decorated to represent the lower jaw and teeth of the figure and in the form 110

shown in Fig. 1, to represent the collar and necktie as shown at 17. The lower jaw strip 10 when the device is in position upon the white keys, will project downward behind the board 18, which extends along and in front of the forward end of the white keys.

In this form, the device is positioned upon the forward end of the white keys so that the strip 10 of each figure will be exactly over a white key, so that as the white keys rise and fall the strip 10 will partake of the movement thereof and cause the impression that the figures are opening and closing their mouths.

15 In Figs. 4, 5 and 6, the device is modified so that the body portion 1 and the strips 21 are formed from a continuous strip for convenience in manufacturing, upon which a strip of paper 43 is secured having represented thereon the heads and the lower jaws of the figures. In this form a suitable blank is provided which will be formed about the base 5 with one end 19 lapped beneath the base 5 to a slight extent, and the forward edge of the blank will be slotted as shown at 20 to produce the flaps or strips 21. The blank will be doubled rearwardly as shown at 22 and secured to the under-surface of the block 5 and thence the strips 21 will be doubled and extended forwardly as shown at 23 and will also be bent as shown at 24 forming the downwardly projecting strips 25. In this form the upper surfaces of the forwardly extending strips 23 will be colored red to represent the tongues and will not be provided with the separate tongues as shown in Figs. 2 and 3. Otherwise than as described, the form shown in Figs. 4, 5 and 6 will be like that shown in Figs. 1, 2 and 3.

40 In this form also the representation of the heads is the width of the white keys of the piano.

Fig. 4 represents a vertical sectional view taken on the dotted line 4—4 in Fig. 5.

45 Figs. 7, 8, 9, 10 and 11 illustrate a form of the device in which the body portion preferably has a vertical front face 26, an inclined rear face 27, and a base 28. Like the other forms it is of indefinite length, and intended to rest upon and cover a plurality of the white keys of a piano. In this form there is secured to the vertical face 26 a vertically disposed panel 29 upon which may appear the representations of the heads of animals, as shown at 30, and the panel 29 is of a size so that it will project downwardly below the base as shown at 30 and be positioned behind the board 18 of the piano, covering the forward ends of the keys. The panel 29 will be provided with openings 31 representing the mouths of the heads and it will also be provided with openings 32 representing the eyes of the heads. In this form each figure is of a width to cover the ends of three keys, the tongue being op-

erated by one key and each eye being operated by the next adjacent keys upon either side of the key which operates the tongue.

Upon the under-surface of the base 28 is secured a folded strip 33 which rests upon one of the white keys and which carries a tongue strip 34, preferably red in color, which projects slightly through the opening 31. Upon the front face 26 is secured a guide strip 35, which is provided with vertical guides 36, in which are arranged slides 37 arranged to have an independent vertical movement and upon which will be indicated eye-balls 38. The slides 37 at their lower ends rest upon the white keys immediately adjacent to and on opposite sides of the key upon which the tongue strip rests, and with the keys normally up the eye-balls are visible, but when either of the keys is depressed the slides 37 fall by gravity and bring a blank part of the slide opposite the eye-openings.

In this form of the device, the device having been properly positioned and the piano being at rest, all the figures will have the appearance like that second from the left-hand end, in Fig. 7, the mouth being closed and the eyes being open; i. e., the eye-balls will be exposed through the eye-openings and the closed mouth will show the forward end of the piano keys. The keys being moved if the center key be depressed, the tongue strip and tongue will fall by gravity with the key, thus producing the effect of an open mouth with the red tongue showing through. It may be that at any given time the tongue only will be depressed, or possibly one key at the right or left of the tongue key may be depressed simultaneously with the tongue key, in which case one of the eye-ball slides will move, and it is possible that all three keys will be depressed simultaneously, in which case both eye-ball slides as well as the tongue strip will be depressed. In any event, as the keys move up and down the tongues and eye-balls will be moved, giving the impression of the animals opening and closing their mouths and winking their eyes.

It will of course be understood that instead of animals, human heads may be shown on the panel 29.

In the form shown in Figs. 12 to 16 the apparatus is substantially the same as that shown in Figs. 7 to 11 but in this form the grotesque heads will be provided with a forwardly extending beak 39 with a forwardly extending flap 40 representing the lower jaw or beak which rests upon one of the white keys, and as the white key is depressed the lower beak or jaw moves downwardly so that the grotesque heads will simulate the opening and closing of their jaws. In this form also the eye-ball slides resting upon adjacent keys move up and down, giving the impres-

sion of winking their eyes. In this form the body portion 41 may be rectangular in cross-section as shown in Figs. 13 and 14 and also as shown in Fig. 16 the forward portion 40 of the beaks may be considerably wider than that portion 42 which rests upon the forward end of the white keys.

Having described my invention, I claim as new—

10 1. A toy comprising a body portion, adapted to rest upon the forward end of a white key of a piano, and provided upon its under-surface with a flap adapted to rest upon and be moved by the movement of a 15 white key of the piano.

2. A toy comprising a body portion carrying upon one face a plurality of heads, mouth openings therein, a tongue flap substantially the width of a piano key secured 20 to the body portion beneath each head, eye openings in the body portion and movable slides carrying eye-balls, arranged to be engaged and operated by the piano keys upon opposite sides of the tongue flaps.

25 3. A toy comprising a body portion, a panel carried thereby showing a plurality of heads, eye-openings therethrough, vertically movable slides carrying eye-balls located at the back of the panel, and projecting 30 below the body portion arranged to be engaged at their lower ends and to be moved vertically.

4. A toy comprising a body portion carrying upon one face the representation of a 35 head with the upper jaw coincident with the base of the body portion, a movable flap carried by the base having represented thereon the lower jaw of the figure, a strip attached at one end to the upper surface of the said 40 flap with its outer end free and projecting to indicate the tongue of the figure, said flap adapted to rest upon the white key of a piano and to be actuated thereby.

45 5. A toy comprising a body portion carrying upon one face the representation of a head, the upper jaw coincident with the base of the body portion, a flap secured at one end to the lower surface of the base and having its lower end projecting downward over the 50 front edge of a white key of a piano showing

thereon the lower jaw of the figure, a strip attached to the upper surface of the flap representing the tongue of the figure, the said flap being rebent to permit it being moved by the movement of the piano key.

55

6. A toy comprising a body portion carrying upon one face a plurality of heads, a plurality of flaps secured to the base representing the lower jaws of the figures, said flap having strip members secured thereto 60 representing the tongues of the figures, each of said flaps being independent of each other and each adapted to be actuated by a key of a piano to impart a vertical movement to the strip.

65

7. A toy comprising a body portion carrying upon one face a plurality of heads, a plurality of independent flaps secured to the base representing the lower jaws of said figures, said flaps each having a strip secured thereto representing the tongue of the figure, each flap being rebent upon itself to permit a vertical movement of the flap and adapted to rest upon and be moved by the movement of a white key of the piano.

75

8. A toy comprising a body portion carrying upon one face a plurality of heads, mouth openings therein, a tongue flap substantially the width of a piano key secured to the body portion beneath each head, said flap 80 being rebent to permit a vertical movement of the flap, eye-openings in the body portion, and movable slides carrying eye-balls, said movable slides and said movable flap arranged to be engaged and operated by the 85 keys of a piano.

9. A toy comprising a body portion carrying upon one face a plurality of heads, each head provided with a forwardly-extending beak, a forwardly-extending flap representing the lower jaw of the figure, substantially the width of a piano key, secured to the body portion beneath each head, said flap being rebent to permit a vertical movement of the flap, eye openings in the body portion, and 90 movable slides carrying eyeballs, said movable slides and said movable flaps arranged to be engaged and operated by the keys of a piano.
